CLAIM

The ornamental design for a bed cover dispenser, as shown and described.

DESCRIPTION

FIG. 1 is a perspective view of an inventive bed cover dispenser;

FIG. 2 is a front view of the bed cover dispenser depicted in FIG. 1;

FIG. 3 is a back view of the bed cover dispenser depicted in FIG. 1;

FIG. 4 is a bottom view of the bed cover dispenser depicted in FIG. 1;

FIG. 5 is a top view of the bed cover dispenser depicted in FIG. 1; and,

FIG. 6 is a left side view of the bed cover dispenser depicted in FIG. 1, where the right side view is mirror image of FIG. 6.

The broken line showing of a roll is for the purpose of illustrating context and forms no part of the claimed design.

1 Claim, 2 Drawing Sheets
